(57) **CLAIM**

The ornamental design for a nut gatherer, as shown and described.

DESCRIPTION

FIG. 1 is a front perspective view of a nut gatherer, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2;

FIG. 11 is a partial enlarged view of FIG. 3;

FIG. 12 is a partial enlarged view of FIG. 4;

FIG. 13 is a partial enlarged view of FIG. 7; and,

FIG. 14 is a partial enlarged view of FIG. 8.

The dashed broken lines in the figures are for the purposes of illustrating portions of the nut gatherer, which form no part of the claimed design.

The dash-dot-dash broken lines are for notating enlarged views, and form no part of the claim design.

1 Claim, 10 Drawing Sheets
